SELF-ADJUSTING RURAL MAIL BOX
SUPPORT

John B. Townsend, Newark, Ohio

Application March 11, 1937, Serial No. 130,399

1 Claim. (Cl. 248—145)

This invention relates to a self-adjusting rural mail box, and more particularly to a support for the box so constructed as to permit the box to swing in either direction should the box be accidentally hit by a passing vehicle and then cause the box to automatically return to its normal position when freed from a blow of a passing vehicle.

An important object of this invention is the production of a simple and efficient rural mail box support which will permit of the placing of the supporting post at a considerable distance from the edge of the highway or main line of traffic and at the same time hold the box within convenient reach of the postman and others desiring access to the box.

Other objects and advantages of this invention will appear throughout the following specification and claim.

In the drawing:

Figure 1 is a side elevation of the mail box and support therefor;

Figure 2 is a top plan view thereof;

Figure 3 is a sectional perspective view of the lower portion of the support, illustrating the locking device;

Figure 4 is a vertical sectional view taken on line 4—4 of Figure 1;

Figure 5 is a horizontal sectional view through the lower portion of the hanger bracket, showing the lower box-supporting arm in a swung position;

Figure 6 is a longitudinal sectional view of the device;

Figure 7 is a transverse sectional view taken on line 7—7 of Figure 5.

By referring to the drawing, it will be seen that 10 designates the supporting post, which may be placed at a considerable distance from the edge of the highway or main lane of traffic.

40 A hanger bracket 11 is bolted or otherwise secured to the face of the post 10 facing the road or highway. The hanger bracket 11 is provided with a pair of spaced downwardly inclined arms 12 and 13, which extend away from the post 10 toward the highway.

A mail box 14 of the conventional type is secured to the upper face and at the outer end of the upper supporting arm 15, and this arm 15 is pivotally connected to the arm 12 of the hanger bracket 11 by means of the pivot bolt 16, the arm 15 overhanging the arm 12. The arm 15 is inclined downwardly from the pivot bolt 16 toward its outer end which supports the mail box 14. A bracing arm 17 engages at its outer end the under face of the arm 15 directly under the mail box 14

and is inclined downwardly toward its inner end, the inner end of the arm 17 having an angular extension 18.

A locking plate 19 is secured to the under face of the angular extension 18, and this locking plate 19 is provided with downwardly bent lips 20 which normally overhang the sides of the arm 13, as shown in Figures 1, 3 and 4. These lips 20 are provided with curved or convex under edges 21, so that they may easily ride or climb upon the upper face of the arm 13 as the arms 17 and 15 are swung at right angles to the arms 12 and 13. A pivot bolt 22 passes through the angular extension 18 and the arm 13 and constitutes a pivot for the arm 17. A coil spring 23 is mounted upon the bolt 22 below the arm 13 and a nut 24 is threaded upon the bolt 22 to regulate the tension of the spring 23. It should be noted that the pivot bolts 16 and 22 are in longitudinal alignment so as to allow the arms 15 and 17 to properly swing.

Should a passing vehicle or other object accidentally strike the box 14, the supporting arms 15 and 17, because of their being pivoted upon the bolts 16 and 18, will permit the box to be swung 25 in the direction of the passing blow and in this manner prevent the breaking of the box or the bending of the supporting arms which might otherwise occur. The arm 17 has sufficient give to allow the convex faces 21 of the lips 20 to ride 30 up over the top face of the arm 13, the spring 23 also yielding sufficiently for this purpose. As soon as the force of the blow has been spent, the weight of the box 14 and arms 15 and 17 will cause the box to swing back to its normal position 35 or to right itself, this movement being facilitated by the rounded or convex under faces of the lips 20 resting upon the upper face of the arm 13. When the box 14 returns to its normal position, the lips 20 will snap over the sides of the arm 40 13 and the locking plate 19 will assume a straddling position with respect to the arm 13, holding the box 14 in its normal position against the usual force of the wind or other force of minor degree which would not be likely to injure the 45 box 14.

Because of the fact that the box 14 is normally supported by the arms 15 and 17 which are inclined downwardly and are pivotally supported upon the arms 12 and 13 which are also inclined 50 downwardly, the pivot bolts being inclined outwardly from the upper end of the post 10, the box 14 will swing upwardly on the arc of a circle in either direction from its central or normal position. Consequently, when the box 14 is released 55

from its swung position, the box through force of gravity will automatically return to its normal position, this movement being facilitated by the rounded contact of the lips 20 with the upper face of the arm 13.

It should be understood that certain detail changes in the mechanical structure may be employed so long as these changes fall within the scope of the appended claim.

Having described the invention, what I claim as new is:—

A self-adjusting mail box support comprising a hanger bracket having a support engaging portion and upper and lower arms extending outwardly therefrom at a downward incline, upper and lower outwardly converging mail box sup-

porting arms, means for pivotally securing one of the mail box supporting arms to one of the arms of said bracket, a bolt pivotally connecting the inner end of the other mail box supporting arm with the other arm of the bracket, a cross plate carried by the second mail box supporting arm and having end portions projecting from opposite sides thereof and bent to form depending lips adapted to engage the side edges of the bracket arm, said lips having arcuate lower edges to facilitate riding of the lips upwardly over the bracket arm as the mail box supporting arms are swung from side to side, and a spring carried by the bolt and yieldably holding the arms in face to face engagement with each other.

JOHN B. TOWNSEND.
